(57) **CLAIM**

We claim the ornamental design for a shelf for refrigerator, as shown and described.

DESCRIPTION

FIG. 1 is a front perspective view of a shelf for refrigerator showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another perspective view thereof;

FIG. 9 is a cross-sectional view taken along line 9-9 of FIG. 2;

FIG. 10 is a front perspective view of a shelf for refrigerator shown in an alternate configuration;

FIG. 11 is front view thereof;

FIG. 12 is a rear view thereof;

FIG. 13 is a left-side view thereof;

FIG. 14 is a right-side view thereof;

FIG. 15 is a top view thereof;

FIG. 16 is a bottom view thereof;

FIG. 17 is another perspective view thereof;

FIG. 18 is a cross-sectional view taken along line 18-18 of FIG. 11;

FIG. 19 is a perspective view of a shelf for refrigerator shown in an alternate configuration;

FIG. 20 is a front view thereof;

FIG. 21 is a rear view thereof;

FIG. 22 is a left-side view thereof;

FIG. 23 is a right-side view thereof;

FIG. 24 is a top view thereof;

FIG. 25 is a bottom view thereof;

FIG. 26 is another perspective view thereof; and,

FIG. 27 is a cross-sectional view taken along line 27-27 of FIG. 20.

The broken lines in the figures depict portions of the shelf for refrigerator which form no part of the claimed design. The dot-dash broken lines define boundaries of the claimed design and form no part thereof.
